UNITED STATES PATENT OFFICE

153,534

DESIGN FOR A COMBINATION CRADLE AND
PERAMBULATOR

Harry B. Light, San Gabriel, Calif.

Application November 23, 1946, Serial No. 135,031

Term of patent 3½ years

(Cl. D5—5)

To all whom it may concern:

Be it known that I, Harry B. Light, a citizen of the United States and residing at San Gabriel, in the county of Los Angeles, State of California, have invented a new, original, and ornamental Design for Combination Cradle and Perambulator, of which the following is a specification, reference being had to the accompanying drawing, forming part thereof, in which:

Fig. 1 is a perspective view of a combination cradle and perambulator as seen from the rear end and one side thereof, showing my new design, and

Fig. 2 is a perspective view of the combination cradle and perambulator as seen from its front end and the side thereof opposite that shown in Fig. 1.

The dominant features of my design reside in the portions shown in solid lines.

I claim:

The ornamental design for a combination cradle and perambulator, substantially as shown and described.

HARRY B. LIGHT.
